JOHN F. ISBELL, OF DENVER, COLORADO, ASSIGNOR OF ONE-HALF TO OTTO Q. BECKWORTH AND JOHN N. ISGRIG, OF DENVER, COLORADO.

HYDRAULIC CLASSIFIER OR SIZER.

SPECIFICATION forming part of Letters Patent No. 729,764, dated June 2, 1903.

Application filed August 18, 1902. Serial No. 120,008. (No model.)

To all whom it may concern:

Be it known that I, JOHN F. ISBELL, a citizen of the United States of America, residing at Denver, in the county of Arapahoe and State of Colorado, have invented certain new and useful Improvements in Hydraulic Classifiers or Sizers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in hydraulic classifiers or sizers whereby pulverized ore in the form of pulp is separated or classified according to the size of the particles, to facilitate concentration.

20 My object is to provide a device of this class which shall be simple in construction, economical in cost, reliable, durable, and efficient in use; and to these ends the invention consists of the features, arrangements, 25 and combinations hereinafter described and claimed, all of which will be fully understood by reference to the accompanying drawings, in which is illustrated an embodiment thereof.

In the drawings, Figure 1 is a central vertical section taken through my improved sizing apparatus. Fig. 2 is a top view of the funnel-shaped mouth, showing the guide-bracket for the upper stem portion of the valve. Fig. 3 shows a number of sizers in side elevation, arranged in suitable proximity to each other, whereby the material which overflows from one passes to the next, and so on. In this view the parts are shown on a greatly-reduced scale.

40 The same reference characters indicate the same parts in all the views.

Let the numeral 5 designate a casing having a funnel-shaped top 5^a, to which is bolted a correspondingly-shaped upper portion 5^b. Below the funnel-shaped top is an enlargement 5^c, forming a chamber for a valve 6, which, as shown in the drawings, is oval or balloon shaped and provided with an upper stem 7 and a lower stem 8. The upper stem 45 passes through an opening formed in a guide-bracket 9, provided with arms 9^a, whose outer

extremities are secured to the inner surface of the funnel-shaped top. The lower stem of the valve passes downwardly through a tube 10 and protrudes at the lower extremity of the device, where it is provided with a hand-wheel 12. The tube 10 fits closely into a part 5^d of the casing below the valve-chamber and passes through a chamber 5^e. Below the chamber 5^e the casing is provided with an interiorly-threaded part 5^f, engaged by an exteriorly-threaded part 10^a, formed in the lower part 10^c of the tube, into which the lower stem of the valve is closely fitted. The part 10^c of the tube passes through a stuffing-box 5^g, applied 60 to the lower extremity of the casing part 5^d. A stuffing-box 10^d is applied to the lower extremity of the tube. The lower stem of the valve passes through this last-named stuffing-box. To the lower extremity of the tube, just 70 above the stuffing-box, is applied a hand-wheel 13, by means of which the tube may be rotated and adjusted vertically in the casing. The valve-stem 8 is provided with a nut 8^a, which engages interior threads 10^e, formed on 75 the portion of the tube passing through the chamber 5^e, whereby the tube and valve are relatively adjusted vertically. The chamber 5^e of the casing is provided with an inlet-tube 14, through which the water required for performing the sizing or classifying function passes. The portion of the tube within the chamber 5^e is provided with elongated openings 15, through which the water enters and passes thence upwardly through the tube, 85 whose upper extremity is outwardly flared or funnel-shaped to correspond with the shape of the adjacent portion of the valve.

Leading downwardly from the chamber 5^d on one side of the casing is a conduit 16, into 90 which is screwed a valved outlet-nozzle 17, through which the classified material after falling downwardly around the valve passes.

Before beginning the operation of the device the valve 6 is adjusted vertically to regulate the space between it and the lower part of the funnel-shaped portion of the casing immediately above the chamber 5^d. This adjustment is accomplished by turning the hand-wheel 12 in the one direction or the other, according as it is necessary to increase or diminish the space between the top of the

valve and the bottom of the funnel through which the sized or classified material passes. The tube 10 is also vertically adjusted to regulate the space between its flared or funnel-shaped upper portion and the valve, whereby the force and quantity of the water passing upwardly around the valve and through the funnel for performing the sizing function is regulated and controlled. The 10 pipe 14 may be connected with any suitable water-supply apparatus adapted to give the required pressure for sizing purposes. As the water passes upwardly from the chamber 5^h, through the tube 10, around the valve, and 15 through the opening in the bottom of the funnel the force of the current raises the smaller or finer particles of ore, while the larger or heavier particles fall downwardly by gravity against this current, passing 20 through the conduit 16 and thence through the valved nozzle 17. The lighter or smaller particles of ore which are carried upwardly by the current of water overflow at the top of the funnel, and if several funnels or sizing 25 devices are used, as shown in Fig. 3, the overflow from the first funnel passes to the next one, where another grade of mineral particles, classified according to their size or fineness, is caught, and so on, until as many 30 grades are taken from the pulp as desired or until the pulp is entirely deprived of its mineral particles, there being as many classes or grades as there are distinct sizing devices employed. The operation may be continued 35 until the pulp is completely deprived of its mineral particles, leaving nothing but clear water to overflow at the top of the last funnel.

When it is desired to vertically adjust the valve and tube independently of each other, 40 one of the hand-wheels 12 or 13 is held against turning while the other is turned.

Having thus described my invention, what I claim is—

1. In a hydraulic classifier or sizer, the combination of an upright casing having a funnel-shaped top, a valve-chamber below the funnel, a reduced part below the valve-chamber, an enlarged part below the reduced part, and another reduced portion below the enlargement, a tube located in said casing filling the reduced portions thereof, passing through the enlargement, and protruding into the valve-chamber, its valve-chamber extremity being outwardly flared or funnel-shaped, the said tube being open where it passes through the enlargement to allow the water to enter, its opposite extremity protruding from the casing, a supply-conduit connected with the casing enlargement, a 50 valve located in the valve-chamber adjacent the lower extremity of the funnel, the lower portion of the valve being surrounded by the upper extremity of the tube, the valve being provided with a stem passing downwardly 55 through the tube which is large enough to

allow the water to flow upward freely around the valve-stem from the casing enlargement, the valve-stem fitting the tube below the casing enlargement and protruding below the same, the tube and valve being adjustable 70 vertically in the casing for the purpose set forth.

2. In a hydraulic classifier or sizer, the combination of an upright casing having an overflow at the top, a valve-chamber in the upper 75 part of the casing, the upper part of said chamber being constructed to form a valve-seat, a valve located in the chamber to control the upward passage of the water and the downward passage of the sized material, the 80 water and sized material passing around the valve which is oval-shaped, the valve having a downwardly-projecting stem whose lower extremity protrudes from the casing, a tube whose upper extremity is located in the valve-chamber and surrounds the valve, and means 85 for introducing water to the tube under pressure whereby it is caused to flow upwardly around the valve, the casing being provided with a lateral passage leading from the valve-chamber below the top of the tube for the escape of the sized material, substantially as described.

3. In a hydraulic classifier or sizer, the combination of a casing having an open top, a 90 valve-chamber below the top, the top of the said chamber being contracted, a valve located in said chamber and arranged to control the passage of material to and from the valve-chamber, a tube whose upper extremity is open 100 and located in the valve-chamber, the valve having a stem passing downwardly through the tube, means for introducing water to the tube under pressure, whereby it is caused to flow upwardly around the valve into the top 105 of the casing, and means for a relative vertical adjustment of the valve and tube within the casing, substantially as described.

4. In a hydraulic classifier or sizer, the combination with a casing having an open top, 110 and a valve-chamber below the casing, of a tube threaded in the casing to permit vertical adjustment, its upper extremity being located in the valve-chamber, means for introducing water under pressure to the tube below the 115 valve-chamber, and a valve located in the said chamber and projecting into the top of the tube, the arrangement being such that the water from the tube is compelled to flow upwardly around the valve into the top of the casing, the valve having a stem threaded in the tube to permit independent vertical adjustment, substantially as described.

In testimony whereof I affix my signature in presence of two witnesses.

JOHN F. ISBELL.
